UNITED STATES PATENT OFFICE

2,611,947

YARN DESIGN FORMING TOOL

Anthony J. Ciroll, Medford, and Philip J. Cannata, Boston, Mass.

Application January 13, 1950, Serial No. 138,428

5 Claims. (Cl. 28—2)

1

This invention relates to a device for forming designs with yarn, such as the flower and pompon design shown and described hereinafter. The principal object of the invention is to provide means for forming such designs rapidly and with uniformity. It is also an object of the invention to make it possible to change the size of the design quickly and easily.

The nature and objects of the invention will best be understood from the following disclosure in conjunction with the accompanying drawing, in which:

Fig. 1 is a side view in elevation of the tool of the invention;

Fig. 2 is a top plan view, partly broken away;

Fig. 3 is a similar view showing a different position of operating parts from that shown in Fig. 2; and

Fig. 4 is a top plan view of a typical product formed with the tool of the invention.

In the drawings, a hollow head 1 is provided with a recess 2 carrying a turnable disc 3 having holes 4 in which one end of a plurality of wire fingers 5 are pivoted. The fingers 5, which are bent as shown, have straight projecting ends 6 which are slidable in openings 7 in a disc or plate 8 which is secured to the head 1. The disc 3 is also secured by any suitable means to a rod 9 enclosed within and coaxial with a tube 10, which serves as a handle. The outer end of rod 9 carries a knurled knob 11. Rotation of knob 11 and consequent rotation of rod 9 turns disc 3 and thereby protrudes the ends of fingers 5 as shown in Fig. 2 or, by opposite rotation, retracts them as shown in Fig. 3.

The top of the tool and the head 1 are covered by a plate or cover 12 secured as by screws 13, and diametrically opposed holes 14 are formed therein which are adapted to receive the pins 15—15 projecting from crosshead 16 removably secured by said pins to said cover plate. Crosshead 16 has a generally convex middle top portion 17 flanked by elevated shoulders 18. The convex portion is substantially throughout its length provided with teeth 19. The lower middle portion of said crosshead is provided with a generally concave portion 20 flanked by slots 21—21 which preferably begin as narrow channels 22 adjacent the curved portion 20 and widen into pear-shaped extremities 23.

In operation, the fingers 5 are protruded, the crosshead is removed, and yarn is passed back and forth diametrically across the top plate and around the fingers 5, each passage across being usually on the next adjacent diagonally opposed

2

fingers from the ones initially chosen to start with. The process is repeated, the fingers being utilized progressively around the head until at least one complete series of loops is formed. If desired, this circuit may be repeated one or more times. Then a needle (not shown) is employed to gather the crossed mid-sections of yarn. Thereupon the crosshead is placed on the cover plate over the looped yarn, and repeated windings, preferably of a different colored yarn, are made transversely of the crosshead from the central concave part to the central convex part. The lower extremities of a wind are held bunched in the concave part, the middle portion of the 10 yarn wind pass across the vertical face and back of the crosshead, and the upper end of the successive winds are held on the teeth 19 and between the shoulders 18. The shoulders prevent displacement of the yarn from the mid-section, while the teeth prevent relative displacement of the windings. Thus the windings can be uniformly and accurately centered with respect to the central part of the loops of yarn held by fingers 5, and the mid-section of the upper winding 15 can be built up. When sufficient material for a top-knot or pompon has been wound, the end is secured with the help of a needle, which on at least some of its strokes will be passed through slots 21—21 to encircle the lower part of the upper winding. Other strokes will penetrate the mid-portion of the looped lower winding. When the top-knot is secured, its upper part is cut along the sides of the toothed portion with scissors. The crosshead is then removed, and, except for 20 any desired final trimming, the pompon is complete. The knob 11 is turned to retract the fingers 5, and the whole design removed. The edges of the loops are secured or otherwise treated in a manner not involving the use of the tool of the 25 invention.

In order to change the size of the petals or loops of the design, the distance travelled in forming each loop may be increased by placing a spacer (not shown) between the cover plate 12 and the 30 base plate 8.

We claim:

1. A tool for forming designs with yarn comprising a flat hollow casing having spaced holes in its peripheral edge, a rotatable disk within 35 said casing carrying a plurality of wire fingers which extend radially through the spaced holes in said casing and over which yarn may be wound, a handle for rotating said disk relative to the casing for retracting said wire fingers within said casing, and a removable cross piece 40
- 50
- 55

mounted diametrically across said casing having a convexly curved serrated upper edge.

2. A tool for forming designs with yarn comprising a flat hollow casing having spaced holes in its peripheral edge, a rotatable disk within said casing carrying a plurality of wire fingers which extend radially through the spaced holes in said casing and over which yarn may be wound, a handle for rotating said disk relative to the casing for retracting said wire fingers within said casing, and a removable cross piece mounted diametrically across said head and at right angles to the plane of said casing.

3. The device according to claim 1 in which said cross piece has a convexly curved serrated upper edge flanked by raised shoulders.

4. The device according to claim 1 in which said cross piece has a convexly curved serrated upper edge and a concave lower edge spaced above the casing.

5. The device according to claim 1 in which

said cross piece has a convexly curved serrated upper edge, a convex lower edge spaced above said casing and slots with narrow necks and widened outer ends extending laterally from said concave lower edge.
